UNITED STATES PATENT OFFICE.

JOHN E. SHEPHERD, OF CHICAGO, ILLINOIS.

FIRE-PROTECTION SIGNAL SYSTEM.

No. 830,254.

Specification of Letters Patent.

Patented Sept. 4, 1906.

Application filed April 25, 1904. Serial No. 204,777.

To all whom it may concern:

Be it known that I, JOHN E. SHEPHERD, of Chicago, in the county of Cook and State of Illinois, have invented certain new and useful Improvements in Fire-Protection Signal Systems; and I hereby declare that the following is a full, clear, and exact description thereof, reference being had to the accompanying drawings, which form part of this specification.

My invention relates to fire-protection signal systems, and has for one of its objects to provide in conjunction with a fire-extinguisher system an alarm system arranged and adapted to cause the transmission of signals to a supervising station upon the occurrence of various troubles in the system and upon the occurrence of fire and consequent commencement of activity in the extinguisher system to send a series of signals in predetermined sequence to the supervising station.

A further object of my invention is to provide such an alarm system wherein the sequential signals transmitted will be distinguishable one from another.

Another object of my invention is to provide such a system adapted for central energization and which will be under constant test.

Other and further objects of my invention will become apparent from the following description.

In the drawings I have indicated in Figure 1 one common system of fire-extinguishing apparatus equipped with a signal system in accordance with my invention. In Fig. 2 I have illustrated the embodiment of a signal system in conjunction with another form of fire-extinguisher system sometimes employed in accordance with my invention.

Throughout the drawings like characters of reference refer always to like parts.

Referring now to Fig. 1, A indicates a riser of a fire-extinguisher system arranged to supply the sprinkler branch pipe *a* upon which the sprinkler-heads are arranged. B indicates a means for supplying water to the pipe A, such means comprising a pressure-tank adapted to contain water under pneumatic or other pressure connected by a pipe *b* with a vertical pipe *b'*, arranged to communicate with the riser A through a connecting-pipe *b*². A secondary means for supplying water to the pipe A is also provided, such means being the gravity supply-tank C, usually mounted at an elevation, generally above the roof of

the building, and connected by a pipe *c*, having therein a check-valve *c'* with the vertical pipe *b'*.

The devices described are parts of a well-known fire-extinguisher system. In practice the sprinkler piping system may be either kept full of air, which balances the water-pressure, or the pipes may be filled with water ready for instant use; but in either event the "blowing" of a sprinkler-head in the pipe *a* causes an instantaneous reduction of pressure in the riser A, and the fluid in the riser A changes from its passive condition of rest into one of activity. Following upon the reduction of pressure in the pipe A the pressure-tank B becomes active and commences to discharge its water into the piping system. While the reduction of pressure in the pipes A and B commence practically simultaneously, as a matter of practice a pressure-recording instrument associated with the pipe A will instantly record the drop of pressure therein and a subsequent restoration of pressure, while the reduction of air-pressure in the tank B is slow and is not noticeable until after the indication thereof in the piping A. I will for brevity, therefore, refer to the period of activity of the pressure-tank as commencing subsequently to the commencement of activity in the pipe A. The gravity-tank C in a system such as that described does not begin to supply water to the piping system until after the pressure in the tank B is reduced so that the check-valve *c'* may unseat, and therefore the commencement of activity in the secondary supply means or gravity-tank C is subsequent to the commencement of activity in the primary supply means or tank B. I associate with each of the pipes A and B the primary means of supply B and the secondary means of supply C a means for indicating the commencement of activity therein. Associated with the pipe A is a pressure-indicator 5, having a hand 6 adapted to sweep over in contact with metallic segment 7, indicating a normal range of pressure variation in the pipe A. Associated with the tank B is a similar gage 8, having a hand 9 and normal-range segment 10; normally arranged in electrical contact.

11 indicates a float arranged within the gravity-tank C and carried by a pivoted lever-arm 12, so that it indicates water-level in the tank. I associate with these devices for indicating the commencement of activity in the various elements of the fire-extinguisher

system a signal system, shown as comprising signal-transmitting devices controlled by said indicating means, signal-responsive devices at the supervisory station, suitable circuit connections between said signal-transmitting and signal-responsive devices, and means for supplying electric energy in said circuit connections.

I have herein shown a particular system of electrical connection of the various devices; but I desire it to be understood that I do not limit myself thereto as to the broader features of my invention.

In the drawings, 13 indicates a central battery, 14 a signal-receiving instrument, 15 a mechanically-tripped signal-transmitting instrument or box, and 17 an electrically-tripped signaling apparatus. The apparatus 17 includes a box proper, 18, normally set and associated with the armature 20 of the electromagnet 21 in any suitable manner, to be tripped and subsequently stopped by the movement of the armature 20 in either direction. The parts may be connected in circuit as follows: From one pole of battery 13 extends a wire 22 to a terminal of the receiving instrument 14, from the other terminal whereof extends a wire 23, connected to one terminal of the transmitting-box 15. From the opposite terminal of the transmitting-box extends a wire 24, connected with one terminal of the signal-transmitting box 18, the opposite terminal of which is connected by wire 25 with one terminal of magnet 21, whose other terminal is connected by wire 26 to the remaining pole of the battery 13. A shunt is provided around the magnet 21 by wire 27, connected to the wire 26, and thence extending to the hand 6 of the pressure indicator 5, located in the pipe A. From the segment 7, with which the hand 6 normally contacts, extends a wire 28, connected to the hand 9 of the indicator 8, associated with the pressure-tank B, while from the segment 10 of said gage or indicator extends a wire 29, connected to the wire 24 of the main circuit. It will thus be seen that a normally closed shunt is provided around the magnet 21, which as long as the gages 5 and 8 show normal pressure remains unbroken. The magnet 21 is so wound that while this shunt is closed it is not sufficiently magnetized to attract its armature 20, but upon the rupture of the shunt it does attract its armature to trip the box 18, and upon the subsequent closure of the shunt-circuit releases the armature. I preferably associate with the tank C a thermometer 30, provided with a temperature-indicating hand 32, arranged to sweep over and in electrical contact with a scale-segment 31, which corresponds with a range of temperature from some temperature above freezing to some temperature below the boiling-point of water. This arrangement is preferably included directly in the wire 24, so that current flowing over

said wire must pass through the segment and hand of the thermometer.

The operation of my system, arranged as above described, will be as follows: If any trouble, such as the reduction of pressure in the pipe A, occurs from some cause which will not affect the pressure-tank B—as, for instance, if the connection of the pipe A with the tank B be cut off and pressure then relieved in said riser A—the hand 6 of the gage 5 moves to indicate a pressure below the normal range, and in so doing breaks contact with its segment 7. Consequently the shunt-circuit around the magnet 21 of the electrically-actuated box 18 is broken and the armature 20 of the magnet attracted to trip the box 18. A signal is accordingly sent by the box 18 over the main line, and it is received by the signal-responsive device 14. This signal being received alone is construed to be a trouble-signal, and suitable precautions may accordingly be taken to restore the piping system to operative condition. In like manner should the pressure in the pressure-tank become unduly reduced the shunt-circuit is broken between the hand 9 and segment 10 of the indicator 8 and trouble-signal is sent in. Reduction of the level of the water in the tank C causes the float 11 to descend, and through any operative connection between the float-lever 12 and the box 15 trips the signal-box and causes a transmission to central of a predetermined signal of said box. This identifies exactly the cause of the trouble as being in the tank. Should, however, a fire occur, so that one or more sprinkler-heads of the pipe a go off, the pressure is instantly reduced in the riser A, and then as activity commences therein and the water rushes through the riser the pressure is again restored to approximately normal condition. This fluctuation of pressure causes the hand 6 to drop away from the segment 7 and then come back into contact with said segment, so that it only momentarily breaks the shunt-circuit 27. Such rupture of the shunt-circuit trips the box 18; but the restoration of the hand 6 to approximately normal position restores the shunt-circuit so that the indicator 8 is able to operate. The pressure in the tank B falls slowly as the water is forced therefrom into the piping system, and after a short lapse of time the hand 9 leaves its segment 10 and again breaks the shunt-circuit around the magnet 21. Accordingly a second signal is transmitted by the box 18 to central station. This sequence of signals may be construed to indicate fire. It will be apparent, however, that it is possible that such sequential signals might follow the accidental blowing of a sprinkler-head; but should the commencement of activity in the sprinkler system be due to such accidental cause steps would naturally at once be taken to cut off the water-supply system tempor-

rarily before the reduction of the supply in the tank C was commenced. No signal therefore would be sent by box 15. When, however, the blowing of a sprinkler-head is due to fire, the flow of water continuing uninterrupted, the pressure-tank soon becomes exhausted and the supply in the gravity-tank C is drawn on. This causes a drop of water-level in the tank C and through the agency of 5 the float and its lever trips the signal-box 15, which transmits its predetermined signal to the supervising-station through the main circuit. When the shunt 27 29 is broken by the drop of pressure in the pressure-tank, the box 10 15 is thereby tripped, but makes only a predetermined number of rounds and then stops. The circuit of box 15 is now complete through the wires 24 25 and the box 18 through the main circuit. It will therefore be apparent 20 that this sequential series of signals indicating, first, the commencement of activity in the piping, second, the commencement of activity in the pressure-tank B, and, third, the commencement of activity water-tank C, 25 constitutes a practically infallible fire-signal and is so construed by those at the supervisory station. To prevent the failure of the system through the freezing of the water in the tank C, I provide the thermometer arrangement, and it will be apparent that should the 30 temperature at any time fall below or rise above limits of safety the main circuit is broken, and by reason of the cessation of current-flow through the signal-receiving instrument 14 notifies the central station of the 35 cause of the trouble.

In Fig. 2 I have illustrated the application of my invention to another system of fire-extinguishing. In said view, A indicates the 40 riser, a the sprinkler-pipe, and d a main connected with the pipe A and having associated therewith a fire or other pump D, which constitutes a means for supplying the pipe A with water under pressure. Such 45 pumps are sometimes arranged to commence operation automatically upon the reduction of pressure in the piping system and in other instances are hand-started; but in either event the commencement of activity in the 50 mechanical means for supplying water to the pipe A is subsequent to the reduction of pressure in the pipe. I provide in conjunction with such pump a means for indicating when its period of activity commences— 55 such, for instance, as a governor d', carrying at its moving end a lever d², one end of which operates in conjunction with a contact d³ to form a circuit-breaker and the other end of which is arranged to mechanically trip a 60 signal-box 15'. The circuit arrangements of the system is just as in the system above described, save that the contact d³ and the arm d² are substituted for the segment 10 and hand 9 of the indicator 8, the box 15' being 65 arranged in same circuit situation as the box

15. Either one of these devices—the circuit-breaker d², d³, or the box 15'—might be omitted without making the system inoperative; but both may be provided as a measure of safety, if desired, and if both are used the 70 box 15' is preferably timed to act more slowly than the box 18. It will be apparent that in general the operation of my system is the same as that heretofore described, a predetermined signal being sent upon the commencement of activity in the riser A and another signal being sent upon the commencement of activity of the means for supplying water to said pipe. It will of course be understood that by the "commencement" of activity in the various elements of the fire-extinguisher system I do not desire to be understood as meaning necessarily the first instant of activity, but the early stages of activity 80 which practice recognizes as the commencement thereof.

It will be apparent from the foregoing description that my invention is applicable to fire-extinguisher systems of widely-different types, and it will further be apparent that in 90 its embodiment various forms of apparatus and wiring arrangements might be used without departing from the spirit and scope of the invention.

Having described my invention, what I 95 claim, and desire to secure by Letters Patent of the United States, is—

1. In a fire-protection system, the combination with an automatic extinguisher system, comprising elements wherein the practical commencement of activity upon the actuation of the system is sequential, of a signal system comprising means associated with the said extinguisher elements for transmitting signals in proper sequence indicative of 105 the practical commencement of activity in the said elements, and signal-responsive apparatus suitably connected with said transmitting means.

2. In a fire-protection system, the combination with an automatic extinguisher system, comprising elements wherein the practical commencement of activity upon the actuation of the system is sequential, of a signal system comprising means associated with the said extinguisher-system elements for transmitting distinguishable signals in proper sequence indicative of the practical commencement of activity in said elements, and signal-responsive apparatus suitably 115 connected with the said transmitting means.

3. In a fire-protection system, the combination with an automatic extinguisher system, comprising elements wherein the practical commencement of activity upon the actuation of the system is sequential, of a signal system comprising means associated with the extinguisher-system elements for transmitting distinguishable signals in proper sequence indicative of the practical commence- 125 130

ment of activity in said elements, signal-responsive apparatus at a central station, suitable circuit connections between the signal transmitting and responsive means, and a 5 single source of current-supply for said circuit connections.

4. In a fire-protection system, the combination with an automatic extinguisher system, comprising elements wherein the practical commencement of activity upon the actuation of the system is sequential, of a signal system comprising means associated with said extinguisher-system elements for transmitting signals in proper sequence upon the 15 practical commencement of activity of said elements, signal-responsive apparatus, a source of current-supply and normally closed circuit connections between said devices of the signal system maintaining said devices 25 under constant test.

5. In a fire-protection system, the combination with an automatic extinguisher system, comprising elements wherein the practical commencement of activity upon the actuation of the system is sequential, of a signal system comprising means associated with said extinguisher-system elements for transmitting distinguishable signals in proper sequence upon the practical commencement 30 of activity in said elements, signal-responsive apparatus, a source of current-supply, and normally closed circuit connections between said devices of the signal system maintaining said devices under constant 35 test.

6. In a fire-protection system, the combination with an automatic extinguisher system, comprising elements wherein the practical commencement of activity upon the actuation 40 of the system is sequential, of a central-energy signal system comprising means associated with said extinguisher-system elements for transmitting distinguishable signals in proper sequence upon the practical commencement 45 of activity in said elements, signal-responsive apparatus, a source of current-supply arranged at a central station, and normally closed circuit connections between said devices of the signal system 50 maintaining said devices under constant test.

7. In a fire-protection system, the combination with an extinguisher system, comprising two means of water-supply arranged 55 to become successively active when the system is in full operation, of an alarm system, comprising means associated with each means of supply for indicating substantially the commencement of activity therein, and 60 means at a supervising-station responsive to the indicating means, whereby the operation of the extinguisher system occasions the transmission of two signals in predetermined sequence to the supervisory station, showing

the successive commencement of activity in 65 the two means of water-supply.

8. In a fire-protection system, the combination with an automatic extinguisher system, comprising a plurality of water-supply means arranged to become successively 70 active when the system is in operation, of an alarm system comprising means associated with each means of water-supply for indicating by a characteristic signal substantially the commencement of activity therein, and means at a supervising-station responsive to the indicating means, whereby the operation of the extinguisher system occasions the transmission of a plurality of distinguishable 75 signals in predetermined sequence to the supervising-station, showing the sequential commencement of practical activity in the said means of water-supply.

9. In a fire-protection system, a piping system wherethrough water flows when the system is active, means for supplying water to said piping system, means arranged in conjunction with said piping system for indicating substantially the commencement of activity therein, means associated with said water-supplying means for indicating substantially the commencement of activity therein, and an electric-signal system, comprising signaling devices controlled by said indicating means, signal-responsive devices, means for supplying electric energy, and circuit connections between the said several devices of the electric system.

10. In a fire-protection system, a piping system wherethrough water flows when the system is active, means for supplying water to said piping system arranged and adapted to become active after the commencement of activity of water-flow in the piping system, means arranged in conjunction with each of said devices for indicating the commencement of activity therein, and an electric-signal system comprising signal-transmitting devices operatively associated with said indicating devices to be actuated thereby, signal-responsive devices, means for supplying electrical energy, and circuit connections between the several devices of the signal system.

11. In a fire-protection system, a piping system wherethrough water flows when the system is active, a primary means for supplying water to said piping system, a secondary means for supplying water to said system arranged to become active after the commencement of activity in the first means, indicating devices associated with each of said water-supply means for indicating the commencement of activity therein, and an electric-signal system comprising signaling devices operatively associated with said indicating devices to transmit signals upon the actuation of said devices, to indicate the

commencement of activity in the supply means with which they are associated, signal-responsive devices, means for supplying electric energy, and circuit connections between said several devices of the electric system.

12. In a fire-protection system, a piping system wherethrough water flows when the system is active, a means for supplying water to said piping system, and other means for supplying water to said system, arranged to become practically active after the commencement of activity in the first supply means, and an electric-signal system consisting of means operatively associated with said supply means for indicating by characteristic distinguishable signals the commencement of activity therein, signal-responsive devices, means for supplying electric energy and circuit connections between the several devices in the electric system.

13. In a fire-protection system, an extinguisher-piping system wherethrough water flows when the system is active, a pressure-tank for supplying water to said piping system, a gravity-tank for supplying water to said system, arranged to become active after the commencement of activity in the pressure-tank, means associated with each of said supply means for indicating activity therein, and a signal system comprising signal-transmitting devices associated with said indicating means for actuation thereby, a signal-responsive device, means for supplying electric energy, and circuit connections between said several devices.

14. In a fire-protection system, an extinguisher-piping system wherethrough water flows when the system is active, and a gravity-tank for supplying water to said system in combination with an electric-alarm system comprising means associated with the piping system and the tank for transmitting distinguishable signals in predetermined sequence upon the practical commencement of activity in the piping system and tank, means responsive to said signals, a source of current-supply, and suitable circuit connections between the devices of the electric system.

15. In a fire-protection system, an extinguisher-piping system wherethrough water flows when the system is active, and a pressure-tank for supplying water to said system, in combination with an alarm system comprising means associated with the piping system and tank for transmitting distinguishable signals in predetermined sequence upon the practical commencement of activity in the piping system and pressure-tank, means responsive to said signal, a source of current-supply, and suitable circuit connections between the several devices of the electric system.

16. In a fire-protection system, an extin-

guisher-piping system wherethrough water flows when the system is active, a gravity-tank for supplying water to said system arranged to become practically active after the commencement of activity in the piping system, means associated with said piping system and said tank for indicating the practical commencement of activity in each thereof, a temperature-indicator associated with the gravity-tank, and a signal system comprising signal-transmitting means associated with said indicators for actuation thereby, signal-responsive means, a source of current-supply, and suitable electrical connections with the devices of the signal system including therein the temperature-indicator.

17. In a fire-protection system, an extinguisher-piping system wherethrough water flows when the system is active, a pressure-tank for supplying water to said piping system, a gravity-tank for supplying water to said piping system arranged to become active after the commencement of activity in the pressure-tank, means associated with each of said means of water-supply for indicating the commencement of activity therein, a temperature-indicator associated with the gravity-tank, and a signal system comprising means associated with each of the activity-indicating means for actuation thereby, signal-responsive means, means for supplying electric energy, and circuit connections for the devices of the electric system including therein the temperature-indicator.

18. In a fire-protection system, a piping system wherethrough water flows when the system is active, a primary means for supplying water to said piping system, a secondary means for supplying water to said system arranged to become active after the commencement of activity in the first means, indicating devices associated with each of said water-supply means for indicating the commencement of activity therein, and an electric-signal system comprising signaling devices operatively associated with said indicating devices to transmit distinguishable signals upon the actuation of said devices, to indicate the commencement of activity in the supply means with which they are associated, signal-responsive devices, means for supplying electric energy, and circuit connections between said several devices of the electric system.

19. In a fire-protection system, an extinguisher-piping system wherethrough water flows when the system is active, a pressure-tank for supplying water to said piping system, a gravity-tank for supplying water to said system, arranged to become active after the commencement of activity in the pressure-tank, means associated with each of said supply means for indicating activity therein, and a signal system comprising means for

transmitting distinguishable signals associated with said indicating means for actuation thereby, to transmit signals distinguishing the functionally-active indicator, a signal-responsive device, means for supplying electric energy, and circuit connections between said several devices.

20. In a fire-protection system, an extinguisher-piping system wherethrough water flows when the system is active, a tank for supplying water to said system, arranged to become practically active after the commencement of activity in said piping system, means associated with said piping system

and said tank for indicating the practical commencement of activity in each thereof, a temperature-indicator associated with said tank, and a signal system comprising means associated with said indicators for actuation thereby, signal-responsive means, a source of current-supply, and suitable electric circuits.

In testimony that I claim the foregoing as my own I affix my signature in presence of two witnesses.

JOHN E. SHEPHERD.
